KURT SCHLEIP, OF ESSEN, GERMANY, ASSIGNOR TO FRIED. KRUPP AKTIENGESELLSCHAFT, OF ESSEN-ON-THE-RUHR, GERMANY.

MEANS FOR CONNECTING THE SHAFTS OF MIXING MACHINES TO THE HUBS OF MIXING OR AGITATING BLADES.

Application filed June 18, 1921. Serial No. 478,762.

To all whom it may concern:

Be it known that I, KURT SCHLEIP, residing at Essen, Germany, a citizen of the German Republic, have invented a certain new and useful Improvement in Means for Connecting the Shafts of Mixing Machines to the Hubs of Mixing or Agitating Blades, of which the following is a specification.

This invention relates to means for connecting the shafts of mixing machines to the hub of the mixing or agitating blades, so constructed that the shaft cannot rotate independently relatively to the blades or be disconnected nor moved longitudinally relatively thereto.

The invention is particularly useful when the material of the blades is, for example, cast silicon that cannot be machined.

The invention will be more fully described and illustrated in the accompanying drawings in which:

Fig. 1 is a vertical section through a mixing machine, and

Fig. 2 is a section on lines 2—2 of Fig. 1. The drive shaft A of the mixer carries on its lower end a head a' of rectangular cross section. The hub b' of the agitator B has a rectangular opening b² of the same cross-sectional dimensions as the head a' of the shaft A. The opening b² forms the entrance to a hollow space b³, otherwise closed on all sides and likewise of rectangular cross section.

To form the connection, the head a' of the shaft A is inserted through the opening b² into the hollow space b³ of the hub b', and is then rotated through 45 degrees relatively to the opening b² (Fig. 2.) The space b³ is then filled with molten material which hardens when cold, for example, lead. The blades B are thereby secured to the drive shaft A against rotation as well as independent longitudinal movement. Since the open-

ing b² and the hollow space b³ can be formed at the time the agitator B is cast, no machining or finishing of the agitator is necessary to connect it to the drive shaft.

Having thus described my invention, what I claim is:

1. A coupling arrangement for connecting two members comprising an angular head carried by one member, the other member being provided with an opening of a corresponding angular shape communicating with a recess formed therein, said head being adapted to enter said recess through said opening and rotated relatively thereto and secured therein by filling said recess with a molten material which is adapted to harden.

2. A coupling arrangement for connecting a pair of parts comprising a rectangular head formed on the end of one of said parts, the other part being formed with a recess having a rectangular opening of smaller dimension, said head being of such dimensions as to enable it to enter said recess through said opening, said shaft being adapted to be rotated through a forty-five degree angle, said recess then receiving molten lead which hardens to permanently secure said head in place within said recess.

3. The method of coupling a member provided with a recess having a rectangular opening of smaller dimension to a second member provided with a rectangular head which consists in inserting the rectangular head of the second member into the recess formed in the first member, rotating the head of said second member through an angle of 45° with respect to the opening of said recess and filling said recess with molten lead, which sets in cooling.

The foregoing specification signed at Essen, Germany, this 7th day of May, 1921.

KURT SCHLEIP.
